TIME-CONTROLLED HEATING DEVICE

Earl J. Wells, Alameda, Calif.

Application February 9, 1931. Serial No. 514,416

4 Claims. (Cl. 200—38)

My invention relates to time controlled heating devices and is particularly applicable to electrical heaters.

Frequently it is desirable to operate electrical heating apparatus so that a predetermined heating effect is produced during a definite time interval and a different heating effect is produced during a subsequent definite time interval. Heretofore, it has been necessary to make changes in the electrical connections manually to effect the desired result or to vary certain rheostats or resistances which may be employed in conjunction with the heater. Manual control of the operation of a heater is objectionable, especially when it is employed in carrying out processes where the time of operation and the temperature are both important.

It is a general object of my invention to provide an automatic time controlled heater of novel construction.

Another object is to provide an electrical heater having means for controlling the operation of the heater at different temperatures during successive time intervals.

Another object is to provide a novel timing device suitable for use in a heater of the character described.

A further object is to provide a novel heating element in a device of the character described in which the heating effect is substantially uniform over the entire area of the element, irrespective of whether it is operating at a high or low temperature and in which the use of separate resistance elements is eliminated.

Another object is to provide a heater of the character described in which the control of the time of operation and of the amount of heat is entirely automatic after the device has been initially set in operation.

These and other objects and advantages are attained in the embodiment of my invention illustrated in the accompanying drawings, in which:

Fig. 1 is an elevational view of an electrical furnace, suitable for use in laboratories, embodying the principles of my invention.

Fig. 2 is a plan view of the device shown in Fig. 1.

Fig. 3 is a cross section of the timing apparatus of the device taken along line 3—3 of Fig. 2.

Fig. 4 is a cross section taken on line 4—4 of Fig. 3.

Fig. 5 is a cross sectional view taken on line 5—5 of Fig. 3, illustrating the construction of

a preferred form of governor for the timing apparatus.

Fig. 6 is a cross sectional view taken on line 6—6 of Fig. 5.

Fig. 7 is a fragmentary view of the governor shown in Fig. 5 illustrating the flow of certain mercury in the governor during the operation thereof.

Figs. 8, 9, 10 and 11 are views, partly diagrammatic, illustrating the operation of certain timing disks employed in the device.

In its preferred form the invention comprises an electrical heater provided with a timing device for automatically controlling the time of operation and the temperature of the heater. The timing device is controlled by a governor which, in its preferred form, comprises a rotatable member having a chamber therein in which a quantity of mercury is placed and is constructed with a labyrinthine obstruction within the chamber so that the gravitational flow of the mercury is retarded. Means can be provided for rotating the governor and preferably the force tending to effect rotation is such that it cannot overcome the retarding effect of the mercury unless the mercury flows below a definite level in the governor. Thus, the rate of rotation of the governor is dependent not only upon the driving force but also upon the rate of flow of the mercury. Means can also be provided for changing the electrical connections in the heater circuit after a definite time interval to change the heating effect of the heater.

In the embodiment illustrated in the drawings, I have shown a furnace which is suitable for use in dental laboratories, but it is to be understood that the principles of the invention can be applied to other types of electrical heating devices.

Referring now to the drawings, I have shown a time controlled heating device comprising a furnace 16 and a timing device 17 both of which can be mounted on a suitable base 18.

The timing device 17 is provided with a suitable housing and comprises a clock-work mechanism 19 and a governor 21 which is adapted to be driven thereby. In the embodiment illustrated the clock-work mechanism is driven by a coil spring 22 having one end 23 thereof secured to the framework and the other end secured to a shaft 24 on which is fixed a gear 26. Gear 26 meshes with a pinion 27 and rigidly secured to the shaft 28 of the pinion 27 is a ratchet wheel 29. Loosely mounted on shaft 28 is a gear 31 carrying a spring biased pivoted

pawl 32 which engages the teeth of the ratchet wheel 29. Gear 31 in turn meshes with a pinion 33 secured on the governor shaft 34.

Thus, when the spring 22 is tensioned a force 5 is applied to the governor shaft 34 through the train of gears forming the clock-work which tends to impart rotation to the shaft 34. The ratchet wheel 29 serves to transmit the force of spring 22 to the governor on the unwinding 10 of the spring, but enables the spring to be wound or tensioned without rotating the governor shaft 34, the teeth of ratchet 29 slipping past the pawl 32 as the spring is being tensioned.

For tensioning the spring 22 an operating lever 36 is provided which is mounted in apertured ears or projections 37 and 38 secured in any suitable manner to a disk 41 loosely carried by a shaft 39. The operating lever 36 is preferably longitudinally slid able in the apertures in ears 37 and 38 and can have secured thereto a collar 42 which serves as an abutment for spring 43 extending between the collar 42 and the ear 38 to bias the lever 36 in the position shown in Fig. 4.

25 Rigidly secured to shaft 39 is a second disk 44 making frictional engagement with the disk 41. A gear 46 which can be formed integrally with the disk 44 or otherwise mounted to rotate therewith is provided which meshes with a pinion 47 fixed to the shaft 24 to which one end of the spring 22 is connected. For operably connecting lever 36 to the gear 46, a projection 48 mounted on gear 46 extends into the path of lever 36 as the latter is moved in a clockwise direction, as viewed in Fig. 4. Thus, upon movement of the lever 36 in a clockwise direction, the spring 22 is tensioned through the medium of gears 46 and pinion 47 meshing therewith. Rotation of pinion 47 effects rotation of shaft 40 24 and the gear 26 thereon which in turn meshes with pinion 27 to rotate the ratchet wheel 29. The rotation of ratchet 29 during the tensioning of the spring is in a clockwise direction, as viewed in Fig. 4 and during this movement of the ratchet the teeth thereof pass under the pawl 32, as hereinbefore mentioned.

The disk 41 has a notch 51 in the periphery thereof and a somewhat similar notch 52 is provided in disk 44. A bell crank lever 53 pivoted 50 about a pin 54 has one arm 56 thereof normally extending into the notches 51 and 52 of the disks and clockwise rotation of the disks 41 and 44, therefore, is normally restrained. To remove the restraint, lever 36 is moved longitudinally 55 against the force of spring 43, whereby the end 57 of the lever 36 abuts against the arm 56 and removes it from the notches 51 and 52. While the arm 56 remains depressed, the lever 36 can be swung in a clockwise direction, carrying 60 with it both of the disks 41 and 44 and also the gear 46, thereby tensioning the spring.

The energy thus stored up in spring 22 is expended in moving the various parts of the timing mechanism and mainly in imparting rotational movement to the governor 21. The governor 21 is secured to the shaft 34 to rotate therewith and is preferably of general cylindrical shape, as illustrated in Figs. 5 and 6. For convenience the governor can be made of suitable moldable material, such as a phenolic condensate product, and, if desired, can be made in two parts, one part including the side wall 61 and the peripheral wall 62 and the other part being in the form of a flat disk 63, serving as 75 the other side wall.

A plurality of partitioning members 64 are provided in the chamber in the governor, each of the partitioning members being substantially of the shape illustrated in Figs. 5 and 6. In the embodiment illustrated, each partitioning member can be formed integrally with the walls 61 and 62 of the governor and comprises a portion 66 extending inwardly from the peripheral wall 62 and a second portion 67 extending in a direction substantially perpendicular to the first portion 66. Each partitioning member preferably extends across the entire distance between the side walls 61 and 63, thus forming a plurality of compartments or stalls opening into the center of the governor.

80 A quantity of mercury 68 is placed within the chamber and normally flows to the position shown in Fig. 5 when the governor is at rest and tends to assume this position when the governor is rotating. For enabling the mercury to flow from one of the stalls to an adjacent stall, the wall 63 has formed therein a groove 69 communicating with adjacent stalls and through which the mercury can flow. In the embodiment illustrated, the groove 69 is annular in 85 shape, for convenience in manufacture, but if desired any other shape of groove or any number of grooves or other passages can be provided for forming a leakage path between adjacent stalls for the flow of mercury. In this manner 90 the labyrinthine path is provided for retarding the flow of mercury as it seeks the lowest level within the chamber. The flow of mercury is thus confined to a path extending along one side of each of the partitioning members 64 and 95 through the passage formed by groove 69.

100 The rotation of the governor when driven by the spring 22 is preferably in the direction of the arrow in Fig. 7. Assuming that the governor is initially at rest and the mercury 68 is at the 105 level illustrated in Fig. 5, a force tending to rotate the governor in the direction of the arrow in Fig. 7 will cause the mercury to be carried to the level shown in Fig. 7. Assuming further 110 that the force is insufficient to carry the mercury to a higher level, the governor will remain at rest at the position shown in Fig. 7 as long as the mercury remains at this level, a condition of equilibrium having been reached. However, 115 grooves 69 permit the flow of mercury from each stall into a lower level in the adjacent stall and at the instant the level is lowered, the force producing the rotation again moves the governor to the position of equilibrium. Thus, the force 120 of spring 22 constantly strives to reach a condition of equilibrium with the retarding force of the mercury 68, and since the level of the mercury is continuously changing by reason of the flow between the stalls, the governor will be 125 caused to rotate continuously in the direction 130 of the arrow. The rate of rotation of the governor is thus determined by the rate of flow of the mercury and by making the groove 69, or other 135 passages which may be provided, larger or smaller in cross section, the rate of rotation can be correspondingly varied provided the force exerted by the spring 22 remains constant.

140 Preferably, the governor 21 is mounted for rotation about a substantially horizontal axis, 145 as illustrated, and the channels 71 formed at the intersection of the partitioning members 64 with the interior peripheral wall 72 can be sloped to direct the flow of mercury toward the groove 69. The interior wall 72 and each of the other 150

walls controlling the flow are also preferably inclined to induce the flow of the mercury toward the groove 69, thereby insuring complete removal of the mercury from each stall before it is moved to the uppermost position. However, should any mercury by chance be carried to the upper part of the governor, the shape of the partitioning walls causes the mercury dropping from one of the uppermost stalls to be deflected into the stalls on the right hand side of the governor, as viewed in Fig. 5, thereby retarding the rotation of the governor and tending to correct the error which might have been caused in the time of operation had the mercury been permitted to be carried over to the left hand side of the governor.

During the rotation of the governor 21, the shaft 24 rotates relatively slowly and the pinion 47 thereon imparts rotation to the gear 26 and the disk 44. The rotation of disk 44 is in a direction opposite to that in which it was rotated during the tensioning of the spring and as the disk 44 rotates, it carries with it the disk 41 with which it is frictionally engaged. Eventually the notches 51 and 52 in the disks will be restored to the starting position adjacent the end 56 of the bellcrank lever 53 and I make use of the time interval required for this restoring motion to effect timing of the apparatus.

The other end 73 of the bellcrank lever 53 is pivotally connected as at 74 to a rod 76 which is provided with a bifurcated contact member 77 at one end. Rod 76 is normally urged to the right as viewed in Fig. 11 by a spring 78 which thereby serves to bias the linkage mechanism so that the arm 56 tends to enter the notches 51 and 52. The bifurcated contact member 77 cooperates with a group of fixed contacts 81, 82 and 83 arranged substantially as shown in Figs. 8 to 11, to form a three-pole switch. The position of the arm 56 of the bellcrank lever 53 controls the portion of the bifurcated contact member 77 and is adapted to move the contact member to three distinct positions, so that it bridges contacts 81 and 82 in one of its positions, contacts 81 and 83 in the second position and in the third position both legs of the bifurcated contact member rest on contact 83. The contacts 81, 82 and 83 can be connected in a circuit with the electrical heating device 16, substantially as shown in Fig. 10, to control the current supplied to the heating device from supply lines 86 and 87. One side of the line can be connected to a contact 88 which engages one end of the heating coil of the heating device 16 and the contacts 82 and 83 can be connected to connecting plugs 89 and 91 which are adapted to be connected to intermediate taps on the heating device.

Assuming that when the part of the heating coil between plug 89 and contact 88 is connected to the circuit, the heating device operates at a low temperature and that when the part of the coil between tap 91 and contact 88 is connected to the circuit, the device operates at a higher temperature, the heating device will be operating at a relatively low temperature when the contact 77 bridges contacts 81 and 82 and will be operating at a higher temperature when the contacts 81 and 83 are bridged. The arrangement of the parts is such that when the bellcrank lever 53 is resting on the peripheral surface of disk 41 as shown in Figs. 9 and 10, the contact member 77 is moved to bridge contacts

81 and 82, thus connecting the heating device for operation at the lower temperature. When the bellcrank lever 53 rests on the peripheral surface of disk 44, however, the contacts 81 and 83 are bridged, thereby connecting the device for operation at the higher temperature. If, on the other hand, both notches 51 and 52 of the disks are coincident and the bellcrank lever 53 has entered both notches, as shown in Fig. 4, the contact member 77 is moved out of engagement with all fixed contacts 81, 82 and 83, thereby breaking the circuit to the heating device 16.

The housing of the timing mechanism can be provided with a scale 92 graduated in minutes or any other time interval and the scale can be placed adjacent a slot 93 through which the actuating lever 36 extends. The scale is calibrated in such a manner that when the lever 36 is moved to a definite position on the scale to tension the spring 22, the notch 52 on disk 44 will not be restored to the initial position until the time indicated by the scale has elapsed. When the notch 51 in disk 41 is not moved relative to the notch 52, notch 51 will also require the time indicated by the scale to return to its initial position. By reason of the frictional engagement between disks 41 and 44, however, the notches 51 and 52 can be adjusted to different positions, in which event a different time interval will be required for the respective notches to return to their initial position.

In setting the timing mechanism the lever 36 is moved longitudinally against the arm 56 of the bellcrank lever 53, as shown in Fig. 8, to move the bellcrank lever out of the notches 51 and 52 and the lever 36 is then swung in a clockwise direction to a position such as that illustrated in Fig. 9. The lever 36 can be moved to any desired position by the operator and by watching the scale 92 the time of operation can be fixed at any value. If for example, the lever when in the position shown in Fig. 9 has been moved to the ten minute position on the scale 92, the device will operate for ten minutes before both notches are restored to the starting point to disconnect the heater. A fixed stop 94 secured in any suitable manner to the frame of the mechanism extends into the path of lever 36 and determines the normal starting position of the apparatus.

After the lever 36 has been moved to the position shown in Fig. 9 and the lever released, the disks will begin their movement back toward the initial position under the influence of spring 22 and governor 21. As heretofore described, the disks 41 and 44 are in frictional engagement with one another and they therefore will move together during the restoring operation. It is not essential however, that the notches 51 and 52 be in unison during the restoring movement and if desired, the lever 36 can be swung in a counter-clockwise direction to an intermediate position as illustrated in Fig. 10, thereby advancing the notch 52. Assuming that the lever when it is in the position shown in Fig. 9 coincides with the ten minute graduation on the scale and when it is in the position in Fig. 10 it indicates four minutes on the scale, the heater will be operated for four minutes at a low temperature and for a six minute interval immediately following it will be operated at a high temperature and at the end of the six minute interval the device will be disconnected from the circuit.

From an inspection of Fig. 10 it will be seen that the bellcrank lever 53 rests on the periphery

of the disk 41 when the parts are in the position shown. Now as disk 44 is rotated it carries with it disk 41 and the two will move in synchronism until the notch 51 reaches a position adjacent
 5 the end of arm 56 whereupon the arm 56 will fall into the notch 51 and rest on the periphery of disk 44, as shown in Fig. 11. Upon this movement the bifurcated contact member 77 is moved from the position shown in Fig. 10 in which it
 10 bridges contacts 81 and 82 to the position shown in Fig. 11 where it engages contacts 81 and 83, thus changing the connections to the heating element from low temperature operation to high temperature operation. At this time the lever
 15 36 strikes the projection 94, thus impeding any further rotation of disk 41. Disk 44 however, is not constrained in its movement at this time and continues its rotation for six minutes longer, in the example chosen, until the notch 52 is
 20 coincident with the end of arm 56. Arm 45 thereupon enters both notches and the bell-crank lever 53 assumes the position shown in Fig. 4, thereby moving the bifurcated contact member 77 to a position to disconnect the heating device.
 25

Thus, the device can be initially set to operate at a definite predetermined period at one temperature and for a subsequent definite period at another temperature. It is to be understood that the plug connectors 89 and 91 can be reversed if desired so that the high temperature is produced for the first period and the low temperature for the second. An audible alarm, such as a gong 96, can be provided which is adapted to be sounded at the end of the second period. For convenience, the striker 97 of the gong can be mounted for movement with the bellcrank lever 53, so that as the end 56 of the lever moves into notch 52, the alarm will be sounded.

40 While I have shown and described a preferred form of my time controlled heating device, it is to be understood that I do not wish to be limited thereto, since the invention as defined in the appended claims can be embodied in a plurality of other forms.

I claim:

1. Timing mechanism for controlling the operation of electrical apparatus for successive time intervals, said mechanism comprising a rotatable shaft, means for driving said shaft at a constant rate of rotation, a circular disc mounted on said shaft for rotation therewith, a second circular disc loosely mounted on said shaft and frictionally engaging said first disc, one of said discs being of greater diameter than the other, each of said discs having a notch in the periphery thereof, the bottom of both notches being disposed at substantially the same radial distance from said shaft, a pivoted lever having an arm extending across the peripheral portion of both discs, means for biasing said arm in such a direction that it tends to enter the notches in said discs, setting means for adjusting said discs in any desired angular relationship relative to each other, rotation of said shaft serving to advance the notches in both discs toward said lever arm, whereby said lever arm enters the notch in the larger of the two discs and rests upon the periphery of the smaller of the two discs after a predetermined time interval, means for retarding the rotation of the larger disc when the notch therein is in the position of registry with the lever arm, continued rotation of the smaller disc serving to advance the notch therein toward the lever arm, where-

by after a predetermined time interval the lever arm enters the notch in the smaller disc, and means controlled by the movement of the lever arm from the periphery of the larger disc to the periphery of the smaller disc and from the periphery of the latter disc to the notch therein for controlling the operation of the electrical apparatus. 80

2. Timing mechanism for controlling the operation of electrical apparatus for successive time intervals, said mechanism comprising a rotatable shaft, means for driving said shaft at a constant rate of rotation, a circular disc mounted on said shaft for rotation therewith, a second circular disc loosely mounted on said shaft and frictionally engaging said first disc, one of said discs being of greater diameter than the other, each of said discs having a notch in the periphery thereof, the bottom of both notches being disposed at substantially the same radial distance from said shaft, a pivoted lever having an arm extending across the peripheral portion of both discs, means for biasing said arm in such a direction that it tends to enter the notches in said discs, setting means for adjusting said discs in any desired angular relationship relative to each other, said setting means comprising a lever carried by the larger disc, a projection extending from the smaller disc into the path of movement of said setting lever when the lever is moved in one direction, whereby both of said discs are turned in unison when said setting lever is moved in one direction, means for holding the smaller disc in its adjusted position, whereby said setting lever can be moved in the opposite direction against the frictional force between the two discs to move the larger disc relative to the smaller disc, rotation of said shaft serving to advance the notches in both discs toward said lever arm, whereby said lever arm enters the notch in the larger of the two discs and rests upon the periphery of the smaller of the two discs after a predetermined time interval, means for retarding the rotation of the larger disc when the notch therein is in the position of registry with the lever arm, continued rotation of the smaller disc serving to advance the notch therein toward the lever arm, whereby after a predetermined time interval the lever arm enters the notch in the smaller disc, and means controlled by the movement of the lever arm from the periphery of the larger disc to the periphery of the smaller disc and from the periphery of the latter disc to the notch therein for controlling the operation of the electrical apparatus 180

3. Timing mechanism for controlling the operation of electrical apparatus for successive time intervals, said mechanism comprising a rotatable shaft, means for driving said shaft at 135 a constant rate of rotation, a circular disc mounted on said shaft for rotation therewith, a second circular disc loosely mounted on said shaft and frictionally engaging said first disc, one of said discs being of greater diameter than 140 the other, each of said discs having a notch in the periphery thereof, the bottom of both notches being disposed at substantially the same radial distance from said shaft, a pivoted lever having an arm extending across the peripheral 145 portion of both discs, means for biasing said arm in such a direction that it tends to enter the notches in said discs, setting means for adjusting said discs in any desired angular relationship relative to each other, rotation of said 150

shaft serving to advance the notches in both discs toward said lever arm, whereby said lever arm enters the notch in the larger of the two discs and rests upon the periphery of the smaller of the two discs after a predetermined time interval, means for retarding the rotation of the larger disc when the notch therein is in the position of registry with the lever arm, continued rotation of the smaller disc serving to advance the notch therein toward the lever arm, whereby after a predetermined time interval the lever arm enters the notch in the smaller disc, and an electric switch operative to three distinct positions in response to movement of said lever arm, each position of said lever arm determining

one position of the switch, the operation of the electrical apparatus being under the control of said switch.

4. Timing mechanism as described in claim 1, in which the setting means comprises a lever carried by the larger disc for effecting turning movement of said disc, one end of said lever being disposed adjacent the notch in said larger disc, and means for supporting said lever for longitudinal movement against the lever arm to eject the arm from engagement with the notch against the force of the biasing means associated with the lever arm.
